SUCTION NOZZLE

George Horace Cranmer, Philadelphia, Pa., assignor to Electrolux Corporation, New York, N. Y., a corporation of Delaware

Application April 23, 1941, Serial No. 389,832

2 Claims. (Cl. 15—155)

My invention relates to suction nozzles and more particularly to suction nozzles for cleaning rugs.

An object of my invention is to provide an improved suction nozzle for cleaning rugs, and particularly for removing embedded dirt therefrom.

What I consider to be novel and my invention may be better understood by reference to the following specification and appended claims when considered in connection with the accompanying drawing, in which

Fig. 1 is a side view of a vacuum cleaner;

Fig. 2 is a front view of my improved suction nozzle;

Fig. 3 is a bottom view; and

Fig. 4 is a side sectional view.

Referring to the drawing, 10 indicates a vacuum cleaner of the so-called tank type in which a dust bag, or dust receptacle, 11 is located in an enclosed casing 12. A flexible hose 13 is connected to an intake opening of casing 12, at one end, and, at the other end, is connected to a suction nozzle 14 with an intermediate, rigid, tubular handle member 15. A motor-fan unit 16 is located in casing 12 for producing a suction. In the operation of this type of vacuum cleaner, nozzle 14 is moved back and forth over a surface being cleaned by means of handle member 15.

In removing embedded dirt from a rug, it is desirable to agitate the rug pile in order to disturb the dirt and dust embedded in it. In my improved construction, this is accomplished by means of two ribs 17 extending parallel and adjacent to an elongated suction opening 18 provided in nozzle 14. At each end of the bottom face of suction nozzle 14, a gliding surface 19 is provided of convex shape for supporting the suction nozzle 14 at the surface of the rug during movement in a forward or rearward direction over the rug surface. Due to the convex surface, the nozzle may be slightly inclined forwardly or rearwardly without interfering with the seal between the nozzle and the rug surface. To insure cleaning adjacent the ends of the suction nozzle 14, openings 20, provided in the gliding surfaces 19, communicate with the suction opening 18 and extend adjacent to the ends of nozzle 14. A connection member 21 is provided connected to the body of nozzle member 14 and adapted to receive the end of a flexible hose or tubular member for connecting the suction nozzle 14 to a source of suction.

In the normal operation of nozzle 14, it is reciprocated over a rug surface and in its move-

ment, the downwardly extending ribs 17 tend to flex the rug pile, as indicated in Fig. 4, thus disturbing the embedded dirt and facilitating its removal by the inflow of air through the rug pile into the suction opening 18. Adjacent to the ribs 17 are smooth lips 22 which engage the top surfaces of rug pile for producing a seal to cause the air to flow downwardly toward the roots of the rug pile for removing embedded dirt. The smooth lips 22 also serve in conjunction with the end surfaces 19 to support the rug nozzle at the surface of the rug pile. The openings 20 communicating with the suction opening 18 serve to insure the cleaning of the rug adjacent to any furniture located thereon within the proximity of nozzle 14 at this opening to the end of the surfaces 19. The ribs 17, in addition to flexing the rug pile, also serve to insure a tight seal between the rug surface and the suction nozzle by extending below the surface at the top of the rug pile. This directs the air entering the suction opening downwardly beneath the surface of the rug pile for removing embedded dirt.

The single narrow rib 17 being located immediately adjacent to the suction opening 18 produces the flexing action of the rug pile right at the suction opening, thus any dirt or dust which is disturbed by the flexing of the rug pile is carried into the suction opening before it can possibly settle back again in the rug pile and become embedded again. The height of the ribs is such as to produce this flexing action without simply bending the rug pile down and compressing it, which would be the case, if the ribs had a greater height.

A narrow rib without an adjacent supporting or gliding surface would embed itself too deeply in the rug, interfering with the ease of movement of the nozzle over the rug surface and also too greatly restricting the air flow beneath it. A relatively wide smooth lip also restricts the air flow by making the air flow path through the rug relatively long. In this construction, the lip does not project beneath the rug surface too far because of the adjoining lip spaced above it and the length of the air flow path through the rug pile is simply the width of the narrow rib. This permits a greater flow of air through the rug surface as well as directing it towards the root of the rug pile.

It is to be understood that my invention is illustrated in a preferred construction, but it is not limited to the details of this construction except as pointed out in the appended claims.

What I claim is:

1. A suction cleaning tool comprising a hollow body having an outlet opening adapted to be connected to a source of suction, said body having an elongated substantially planar face with an inlet opening therein extending throughout most of its length, a surface on said face extending along both sides of said inlet opening, said surface forming a wide band on each side of said inlet opening and spaced slightly therefrom, one long thin bead formed on said face along each long side of said inlet opening in the space between said inlet opening and said band, said beads extending slightly downwardly beyond the plane of said face, said face having members projecting from each end thereof, said members having large nearly planar surfaces parallel to the plane of said face, said members extending downwardly beyond said face a greater distance than said beads and sufficiently far to prevent 20 said beads from penetrating the pile of a rug

being cleaned except just enough to flex the extreme ends thereof as the nozzle passes over a rug being cleaned, said band being adapted to seal against the rug being cleaned.

2. A suction nozzle including a body member having an elongated suction opening in one face, a wide lip extending along each side of said suction opening, an extension forming a gliding surface at each end of said suction opening and extending downwardly beyond said lips, said lips having narrow ribs projecting downwardly therefrom a lesser distance than said gliding surfaces, said ribs being joined to said lips in airtight relation throughout their length and extending parallel with and adjacent to said opening, said extensions having openings communicating with said suction opening and extending substantially to the ends of said gliding surfaces, and a connection member communicating with the interior of said body member.

GEORGE HORACE CRANMER.
